UNITED STATES PATENT OFFICE.

WALTER THISSEN, OF SAYRE, PENNSYLVANIA.

WEDGE-BOLT.

SPECIFICATION forming part of Letters Patent No. 792,181, dated June 13, 1905.

Application filed December 22, 1904. Serial No. 237,942.

To all whom it may concern:

Be it known that I, WALTER THISSEN, a citizen of the United States, residing at Sayre, in the county of Bradford and State of Pennsylvania, have invented a new and useful Improvement in Wedge-Bolts, of which the following is a specification.

My invention relates to an improvement in the bolts by which the wedge-blocks are adjusted in the pedestals for the journal-boxes of locomotive driving-wheel axles. The life of these wedge-bolts, owing to the continued jar and strain to which they are subjected, is of short duration and they have to be continually replaced. Heretofore, in order to insert a new bolt it has been necessary to remove the pedestal-brace at the bottom of the pedestal-legs, which consumes considerable time and frequently permits the journal-box to be thrown out of alignment or to become cramped in the pedestal.

The object of my improvement is, therefore, to provide means whereby these wedge-bolts may be renewed from time to time in an expeditious manner and without the necessity of removing or displacing any parts of the locomotive-frame.

I accomplish my object by means of a screw-threaded block pivoted in a slotted chamber in the pedestal-brace whereby the wedge-bolt may be screwed into and through the block and afterward thrown into proper alignment and engagement with the wedge-block, as illustrated in the accompanying drawings, in which—

Figure 1 represents a side elevation of a portion of a locomotive-frame, showing the pedestal-legs for a main driver journal-box with my improved wedge-bolt construction applied thereto; Fig. 2, a transverse section of the same, showing an end view of the wedge-block and the wedge-bolt block; and Fig. 3, a detail showing the wedge-bolt in position to be thrown into engagement with the wedge-block.

Like letters designate like parts in the several views.

A represents a portion of a locomotive-frame with the pedestal-legs for the journal-box C of a main driving-axle B. One leg of

the pedestal stands vertically and is provided with the shoe D, which extends from top to bottom of the pedestal and forms a bearing for one side of the journal-box C. The other leg is inclined on its inner side to receive the wedge-block E, which is adapted to be adjusted by the bolt G, so as to permit the journal-box C to slide in the pedestal-frame without side play. In order that the wedge-block may be raised or lowered in adjusting it, the wedge-bolt G is provided with a head H, which engages a grooved slot at the lower end of the wedge-block, and it will be evident that in order to insert this head in the slot the wedge-bolt must be moved to one side. To accomplish this side movement without removing the pedestal-brace F, I pivot a screw-threaded block I in a slot K, formed in the pedestal-brace, said slot being provided at front and rear with inclined sides L, so as to permit the block I to be tilted to one side on its trunnions J. This permits sufficient side motion in the wedge-bolt to allow the head to be thrown into or out of engagement with the wedge-block, as shown in Fig. 3.

When a wedge-bolt becomes broken, the parts will be removed from the wedge-block and from the block I and a new bolt will be inserted by screwing it through the block, the head H being of a diameter corresponding with the threaded hole in the block. When the head has been brought into alignment with the slot in the wedge-block E, the bolt will be turned to vertical position and into engagement with said slot, the sides of the block I coming against the vertical sides of the slot K when in this position. After the wedge-block has been properly adjusted by screwing the bolt G up or down to the required extent the flanged nut M will be screwed up against the bottom of the pedestal-brace F, thereby locking the block in its vertical position, and the parts will be further secured from displacement by means of the jam-nut N. In order to form the slotted chamber K to receive the block I and to insert said block in place, I make the pedestal-brace F in two parts, fastening the halves together by cross-bolts and securing said brace to the main frame by means of vertical bolts in the usual

manner, as illustrated in Fig. 1 of the drawings.

Having thus described my improved wedge-bolt construction, what I claim as my invention, and desire to secure by Letters Patent, is—

1. The combination, with a pedestal-brace, of a swivel-block housed in the brace, and a wedge-bolt adapted to pass through said block.
2. The combination, with a pedestal-brace made in two parts, of a swivel-block housed in a slot between said parts, and a wedge-bolt adapted to be screwed through said block.

3. The combination, with a pedestal-brace, of a swivel-block housed in a slot passing ¹⁵ through the brace, a wedge-bolt adapted to be screwed through said block, and a nut on the bolt to lock the block and bolt in their normal and adjusted positions.

In testimony whereof I have affixed my signature in presence of two witnesses.

WALTER THISSEN.
